UNITED STATES PATENT OFFICE.

WERNER OCHS, OF BAD LIEBENSTEIN, GERMANY.

EYELET-INSERTING MACHINE.

Application filed January 16, 1923. Serial No. 613,057.

To all whom it may concern:

Be it known that I, WERNER OCHS, residing at Bad Liebenstein, Germany, have invented certain new and useful Improvements 5 in Eyelet-Inserting Machines, of which the following is a specification.

This invention relates to a machine for inserting eyelets in labels, advertising sheets, documents, leather, fabric or the like and 10 more especially to an improved device for feeding the eyelets which permits the arranging of the eyelet-reservoir in the handle of the machine, and it relates further to an improved mechanism for gripping the eyelets and for conveying the same to the setting die. This invention has for its object 15 to provide a simple, reliable, automatic machine the main parts of which may be either pressed, stamped or drawn from sheet iron thereby permitting the machine to be manufactured in large quantities at a minimum 20 expense.

A form of construction of the improved machine is shown by way of example on the 25 accompanying drawing, wherein:

Fig. 1 shows the machine in side elevation, partly in section in the position of rest.

Fig. 2 shows in side elevation, partly in section, parts of the machine, the front wall 30 is shown as removed and the parts of the machine are shown in the positions which they assume at the instant at which the eyelet is being taken by the catch pin.

Fig. 3 is a view similar to Fig. 2 in which 35 the parts are shown in the positions which they assume at the instant of the flanging of an eyelet.

Fig. 4 is a view similar to Fig. 2 in which 40 the parts are shown in the positions which they assume during the return to the initial positions.

Fig. 5 is a front elevation.

Fig. 6 is a plan view on line A—B of 45 Fig. 4.

Fig. 7 is a cross section through the eyelet reservoir on line C—D of Fig. 6.

The frame of the machine is composed of the two side walls 1, 1 connected by the bed plate 2 and the cross bar 3. At the center 50 of the frame the pressure lever of the machine is arranged so that it can oscillate around the pivot pin 4. This pressure lever consists of the eyelet reservoir 5 and the cheeks 6 rigidly connected with said reservoir. In the eyelet reservoir, which serves 55 at the same time as handle and which is

preferably of cylindrical shape, an eyelet-channel 8 with lateral oblique inlet openings 7 is arranged, which is covered by a plate 32 overlapping at both sides. The orifice of the eyelet channel 8 turned towards the fulcrum is connected with a raceway 9 located at or in the pressure lever. The outer end of the eyelet reservoir is closed by a lid 10. After the lid 10 has been removed the eyelets are filled into the reservoir and by the oscillating movement of the lever the eyelets are moved through lateral inlets of the channel and are fed into the raceway. The inner end of the eyelet reservoir is mounted 60 in a sheet iron sleeve 11 upon which the two sheet iron cheeks 6 are fixed which are pivotally fixed upon the pin 4. The eyelet reservoir, sleeve and cheeks form, as already mentioned above, a rigid whole which serves 65 as pressure or operating lever. Between the cheeks 6 a sheet iron plate 12 is fixed which serves as a bottom for the raceway 9. Upon each cheek 6 are fixed bars 13 which serve as guides for the eyelets. The end 70 of the raceway which is situated under the pivot pin 4 is closed by elastic tongues 14. The cheeks 6 have each a downwardly directed extension 15. In these extensions 15 a bolt 16 is fixed which serves as pivot for 75 the set piston 17 which is pulled to the right by the action of a spring 18. The set piston 17 has a lateral extension 19 with laterally projecting studs 20 bearing against the extensions 15 of cheeks 6 and limiting thus 80 the oscillation of the set piston in the right hand side direction. This is the position of rest of the set piston which stands exactly under the front eyelet in the raceway 9, which eyelet is retained by the elastic 85 tongues 14. The set piston 17 is perforated and the pivot bolt 16 has a cross boring. A catch pin 21 is inserted into these two 90 borings so that it engages with the set piston. The catch pin 21 is secured in its position by friction so that it can be easily displaced. The catch pin projects downwards 95 from the set piston so that at the depression of handle 5 it comes in contact with an inclined surface 22 and is pushed inward until 100 it engages with the eyelet situated over it. If the depressing of the hand lever continues the laterally projecting studs 20 moving along the curved edges 23, 23 upon the inner side of each frame 1, 1 communicate 105 to the set piston 17 an oscillating movement in left hand side direction until the studs 20

have reached the concentric part 24 of the curves 23.

During this movement the catch pin 21 which is pushed upward removes the front eyelet from the raceway 9 by pushing it past the elastic tongues 14. The eyelet sits now loosely upon the catch pin of the set piston and, moving along the path indicated in dotted lines in Fig. 2 and remaining 10 below the mouth of the machine, it gets below the upper die 25. If the depression of the hand lever 5 is now completed, the set piston remains at rest with regard to the hand lever and it is moved towards the 15 upper die 25 along an arc-shaped path as if the eyelet was mounted upon the left end of a rigid two-armed lever so that the eyelet is engaged by the die 25, pressed into the material and flanged. The centering pin 20 26 of the die 25 presses back the catch pin 21 into its initial position until the downward movement is completed (Fig. 3). At the succeeding upward movement caused by the pull spring 30 the catch pin comes in contact 25 with the inclined surface 22 from the left hand side (Fig. 4) and makes the same oscillate towards the right around pivot pin 27 until the catch pin is released whereupon the inclined surface is returned into the 30 initial position by the action of spring 28, the position being determined by the nose 29 coming in contact with the cross bar 3. The pressure lever, set piston, catch pin and other parts have also adopted their initial 35 positions and the next operation can begin, a fresh eyelet having been fed to the front end of the raceway.

In order to prevent the eyelets in the raceway from sliding back into the channel 40 when the eyelet reservoir is being pressed downward, the transition from the channel to the raceway is stepped. The step 31 acts like a check valve, so that the eyes are generally prevented from sliding back into the 45 channel.

What I claim is:

1. An eyelet inserting machine comprising a frame, a pressure lever mounted therein, an eyelet reservoir forming an extension of said pressure lever and serving as an operating handle therefor, an eyelet set oscillably mounted on said pressure lever, a catch pin mounted in said eyelet set, an eyelet raceway on said pressure lever, a co- 50 operating set mounted on said frame and 55

stationary cam means for causing the eyelet set on the pressure lever to move from a position under the end of the raceway into a position where it is adapted to cooperate with the set on the frame. 60

2. An eyelet inserting machine comprising a frame, a pressure lever mounted therein, a rod-shaped eyelet reservoir forming an extension of said pressure lever and serving as an operating handle therefor, an eyelet 65 channel in said eyelet reservoir having oblique inlets at the sides displaced the one with regard to the other, a catch plate closing said eyelet channel at the top and overlapping at both sides, an eyelet set oscillably mounted on said pressure lever, a catch pin mounted in said eyelet set, an eyelet raceway on said pressure lever, a cooperating set mounted on said frame and stationary 70 cam means for causing the eyelet set on the 75 pressure lever to move from a position under the end of the raceway into a position where it is adapted to cooperate with the set on the frame.

3. An eyelet inserting machine comprising a frame, a pressure lever mounted therein, an eyelet reservoir forming an extension of said pressure lever and serving as an operating handle therefor, an eyelet set oscillably mounted on said pressure lever, 80 a catch pin mounted in said eyelet set, an eyelet raceway on said pressure lever, a cooperating set mounted on said frame and stationary cam means for causing the eyelet set on the pressure lever to move from a 85 position under the end of the raceway into a position where it is adapted to cooperate with the set on the frame, and an oscillable inclined guiding surface for guiding said catch pin into the raceway for the eyelets 90 before said raceway has adopted a position below the horizontal, for holding said catch pin in this advanced position until it is depressed again at the flanging of the eyelet by the riveting die, said catch pin causing, 100 when returned to the initial position, said inclined surface to oscillate around its pivot.

In testimony whereof I affix my signature in presence of two witnesses.

WERNER OCHS.
